2 Claims. (Cl. 167—65)

The present invention relates to new tranquilizer compositions and more particularly to new tranquilizer compositions containing, as active agent, 10-chloro deserpidine, and to a process of using such compositions in therapy.

The present application is a continuation-in-part of co-pending application Serial No. 727,777, filed April 11, 1958, now abandoned.

The valuable neuro-depressive activity of reserpine is well known. This activity, however, is accompanied by a number of disadvantages. While it suppresses in pathological cases a number of useless and undesired reactions due to its tranquilizing effect, it also has a depressive effect upon those functions necessary for carrying out useful or desired physiological reactions. Frequently it produces drowsiness and disinterestedness to the outside world, sometimes even profound apathy.

It is one object of the present invention to provide new tranquilizer compositions which avoid all the inconveniences and disadvantages and especially the neuro-depressive effects encountered on administration of reserpine, while retaining all the desirable tranquilizing effects ordinarily achieved by reserpine.

Another object of the present invention consists in providing a process of tranquilizing patients by administration of such new and valuable pharmaceutical compositions.

Other objects of the present invention and advantageous features thereof will become apparent as the description proceeds.

10-chloro deserpidine, the active agent according to the present invention, is prepared according to the process described in copending patent application Serial No. 727,777, filed April 11, 1958, now abandoned.

Investigations were carried out to separate these two effects, the desired tranquilizing effect and the undesired neuro-depressive effect, and, thus, to supply products which will be useful as tranquilizers but which, at the same time, have only an insignificant depressive activity, i.e. which do not affect normal behavior.

To test such compounds, the amphetamine test as described by L. Lasagna and W. P. McCann "Science," vol. 125, page 1241 (1957), and by J. H. Burn and R. Hobbs, "Arch. Int. Pharmacodyn." vol. 113, page 290 (1958), was used. This test is based on the known fact studied more particularly by Chance, that the mortality rate in mice, due to the administration of amphetamine, is considerably increased if the animals are kept in groups instead of being isolated in individual boxes. This significant increase in mortality rates is caused by the "transmission" of the state of excitement from one mouse to another. Their aggressiveness and their panic-like fear induce fatal paroxysms when kept in groups. The capacity of a drug of reducing this significant increase in mortality, due to the confinement of the animals, defines and determines according to said test, the tranquilizing activity of the drug.

Simultaneous presence of tranquilizing activity and general neuro-depressive activity prevents rational exploita-

2

tion of the first mentioned property, which, from the therapeutic view point, is of greater interest.

The new pharmaceutical compositions according to the present invention possess very remarkable tranquilizing activity without exerting undesirable neuro-depressive effects.

According to the present invention, it has been found quite surprisingly that it is possible to dissociate said two activities of reserpine by using an analogous compound, 10, namely, 10-chloro deserpidine. This compound has a tranquilizing effect which is substantially equal to that of reserpine, while it exerts only a negligible depressive effect on the central nervous system. Its depressive activity is only about one-tenth to one fortieth of that of reserpine. 15 Compositions based on 10-chloro deserpidine possess also a considerably lower toxicity than reserpine. Furthermore, the sensitizing effect of reserpine induced by cerebral electrical excitation of the brain and by maximum electric shock treatment is also found to be very much lower with the new compositions according to the present invention than with reserpine.

Consequently, the present invention provides a drug of the reserpine series which is a highly effective and reliable tranquilizer without exerting a general neuro-depressive effect.

Other advantages of this invention will be apparent to specialists in the field.

In principle, pharmaceutical compositions according to the present invention are prepared by combining 10-chloro deserpidine with the appropriate pharmaceutical excipients which may be solid or liquid. Solid compositions may be in the form of tablets, lozenges, coated tablets or dragees, pills, capsules, or powders, or in the form of fluid preparations such as solutions, emulsions, suspensions, sirups, or elixirs.

They may also be used in the form of suppositories or may be administered in any other form.

In the case of powders, a fine dispersion of the active compound is of importance for accuracy in dosage. Such 40 a fine dispersion can be achieved, for instance, by intimately mixing and milling the compound in a ball mill with a solid, pulverulent extending agent to the desired degree of fineness or by impregnating the already milled, finely powdered, solid carrier with a mixture of the active compound 45 dissolved in water or any other suitable solvent and then removing the water or solvent.

To prepare the solid shaped compositions such as tablets, pills, lozenges, and other solid forms suitable for administration of the active agent, the conventional extending, diluting, binding agents, lubricants, and other 50 tableting adjuvants such as sugar, lactose, sorbitol, talc, starch, pectin, gelatin, gum arabic, methyl cellulose, carboxy methyl cellulose, preferably in the form of its sodium salt, yeast extracts, agar, calcium sulfate and calcium carbonate, kaolin, stearic acid, magnesium stearate, and/or solubilizing agents such as alcohol, chloroform, trichloro ethylene, and the like are used.

The content of active principle in these compositions 55 may vary. It is, of course, necessary that the active compound be present in such an amount that a suitable dosage will be ensured per dosage unit. The content of the new compositions may be between about 0.01% and about 10%. Larger amounts may, of course, also be incorporated although with such larger amounts accurate dosing 65 will be more difficult.

The average dose is between about 0.1 mg. and 10.0 mg. per day, taken subdivided in 3 or 4 doses, but daily doses as high as 30 mg. can be taken without danger, if necessary.

70 It is also to be understood that 10-chloro deserpidine may be used in combination with other drugs or may be

administered to solid or liquid foods without exceeding the scope of the present invention.

The following examples and experimental results will serve to illustrate the present invention, without, however, limiting the same thereto. In all of the examples the levorotatory enantiomorph of 10-chloro deserpipine is used as active agent.

EXAMPLE 1.—PREPARATION OF TABLETS

100 g. of 10-chloro deserpipine are mixed with 400 g. of sugar, 8,870 g. of lactose, 4,600 g. of starch, and 130 g.

5

The mortality percentages obtained by totaling all the tests of Table I produce an almost linear function when the logarithm of the dose injected is plotted graphically. The slope of the straight line thus obtained is slight, indicating gradual effects over an extended posologic zone. The attached graph FIG. 1 illustrates these results.

In order to compare quantitatively the tranquilizing effect of 10-chloro deserpipine and of reserpine, tests on 220 mice were carried out simultaneously under the same conditions as described above with these two products. The result of these tests are shown in Table II.

TABLE II.—COMPARISON OF THE EFFECT OF 10-CHLORO DESERPIDINE AND OF RESERPINE, INJECTED INTRAPERITONEOUSLY, ON THE MORTALITY OF GROUPS OF TEN MICE WHICH RECEIVED, ALSO INTRAPERITONEOUSLY, 40 MG./KG. OF AMPHETAMINE

Doses in mg./kg.	Number of dead mice found in each group of 10								Total Mortality		Percentage Mortality	
	Test 1		Test 2		Test 3		Test 4		A	B	A	B
	A	B	A	B	A	B	A	B				
	0	10	7	8	10	10	21/40	23/40	53	58	42	35
0.2	5	4	4	4	5	5	21/40	23/40				
0.5	6	4	1	2	5	4	17/40	14/40				

of gelatin. The resulting homogeneous powder is moistened, granulated, and forced through an apertured plate or a sieve of screening wire of adequate dimensions.

After drying, the granulated material is ground; then lubricated by the addition of 750 g. of talc and 150 g. of magnesium stearate. The mixture is then compressed to tablets weighing 150 mg. each and containing 1 mg. of active principle.

EXAMPLE 2.—PREPARATION OF A SOLUTION

0.4 g. of 10-chloro deserpipine are mixed with 4 g. of tartaric acid, 18 g. of benzyl alcohol, 400 cc. of polyethylene glycol 400, and with a quantity of distilled water sufficient to produce a volume of 2000 cc.

The solution thus prepared contains 0.4 mg. of active agent per 2 cc. It is administered both by intravenous and intramuscular injection.

EXAMPLE 3.—TESTS ON ANIMALS

1. Tests of tranquilizing activity by intraperitoneal injection

A 40 mg./kg. dose of amphetamine when injected intraperitoneally into groups of ten mice produced an average mortality of 88%. The compounds of the reserpine series to be compared are administered, also by intraperitoneal injection, 1½ hours before the injection of amphetamine. Each test included a group of 10 control animals which, in place of active agent, received solely the solvent, likewise 1½ hours before amphetamine injection.

The results obtained on administration of varying amounts of 10-chloro deserpipine are given in Table I.

In said Table II

A indicates 10-chloro deserpipine.

B indicates reserpine.

The attached graph FIG. 2 illustrates the results obtained in these comparative tests and shows that the two compounds have about the same tranquilizing activity.

II. Test for depressive activity

In this test the depressive activity was determined by the tumbling effect on mice placed in groups of 5 in a horizontal cylinder rotating about its axis. The untreated mice were able to maintain their equilibrium by placing themselves contrary to the movement of the cylinder. The speed of the cylinder was adjusted in such a manner that the number of falls per animal did not exceed four during a four-minute test. The abatement of the reflexes increases the number of falls in a manner obviously in relation to the dose of active agent injected, thus making it possible to evaluate the intensity of the action of the product to be tested.

The mice are observed one hour or, respectively, four hours after intraperitoneal injection of the compound to be tested and once every day on four subsequent days. The attached graph FIG. 3 shows the results obtained in this test with 10-chloro deserpipine as compared with reserpine.

The amounts injected intraperitoneally are indicated in mg./kg. at the beginning of each curve.

This graph FIG. 3 proves that the depressive state caused by a dose of 20 mg./kg. of 10-chloro deserpipine is scarcely more pronounced than that produced by the

TABLE I.—EFFECTS OF 10-CHLORO DESERPIDINE, INJECTED INTRAPERITONEOUSLY, ON THE MORTALITY OF GROUPS OF 10 MICE, WHICH RECEIVED, ALSO INTRAPERITONEOUSLY, 40 MG./KG. OF AMPHETAMINE

Doses of 10-chloro deserpipine in mg./kg.	Number of dead mice found in each group						Total Mortality	Percentage Mortality
	Test 1	Test 2	Test 3	Test 4	Test 5	Test 6		
0	6	10	9	7	8	10	50/60	83
0.1							6/10	60
0.2	5	8	4	4	8	29/50	58	
0.5	6	9	1	5	5	26/50	52	
1	3	3	7	2	4	23/60	38	
2	4	3	5	2	3	17/50	34	
5	2	3	2	5	2	14/50	28	

this test with 10-chloro deserpine as compared with reserpine.

The test used to determine the threshold of sensitivity to electric shock in rats is that described by Woodbury and Davenport "Arch. Int. Pharmacodyn." vol. 92, page 97 (1952).

10-chloro deserpine and reserpine are injected intraperitoneally in various doses. Table VI shows the average threshold values observed in groups of 10 rats.

TABLE VI.—COMPARISON OF THE EFFECT OF 10-CHLORO DESERPINE AND OF RESERPINE ON THE THRESHOLD VALUE OF SENSITIVITY TO ELECTRIC SHOCK IN RATS

Compound injected	Dose in mg./kg.	Average electric shock threshold value (in volts) in groups of 10 rats.		
		Before injection	1½ hours after injection	4 hours after injection
10-chloro deserpine	0.2	116.5	115.5	117.5
	0.5	119.5	117.5	119.5
	2	119.0	116.5	113
	5	120.0	117.5	107
Reserpine	0.2	114.5	113.5	111.5
	0.5	119.5	118.5	109
	2	120	102.5	92
	5	115	75	80
Control	0	119.5	118.5	116.5

It is evident that reserpine considerably lowers the electric shock threshold values in doses of 2 mg./kg. and 5 mg./kg. whereas 10-chloro deserpine, even when used in a dose of 5 mg./kg. only causes a lowering of the threshold value comparable to that of 0.5 mg./kg. of reserpine.

The increased sensitivity of patients treated with reserpine to electric shock is well known. It was of interest, therefore, to determine whether 10-chloro deserpine would have a similar modifying effect on the maximum crisis of rats as reserpine. As is shown by the following Table VII, reserpine increases the number of maximum crises already by intraperitoneal administration of a dose of 0.5 mg./kg. In contrast thereto 10-chloro deserpine produces a comparable increase only with a dose of 5 mg./kg. under the same conditions.

TABLE VII.—COMPARISON OF THE EFFECT OF 10-CHLORO DESERPINE AND RESERPINE ON THE FREQUENCY OF OCCURRENCE OF MAXIMUM CRISES IN RATS SUBJECTED TO AN ELECTRIC SHOCK TREATMENT WITH A CURRENT OF 180 V. (CORRESPONDING TO 20 M. AMP. UNDER THE CONDITIONS OF THIS EXPERIMENT)

Compounds Injected	Doses in Mg./kg.	Number of maximum crises in 10 rats subjected to electric shock treatment		
		Before Injection	2 hours after injection	4 hours after injection
0		3	4	2
0		4	2	2
10-chloro deserpine	1	3	3	1
Do	5	2	10	9
Reserpine	0.5	2	10	10
Do	1	3	8	8

VI. Toxicity

(a) *Acute toxicity*.—10-chloro deserpine, injected intraperitoneally, does not cause any death in mice until a dose of 20 mg./kg. is administered. This corresponds to the toxicity of the solvent used. A supplementary test was carried out using a suspension and administering 50 mg./kg.; 100 mg./kg.; 250 mg./kg.; 1 g./kg.; and 1.5 g./kg. Only the two highest doses resulted in death to 11 days after the injection (4 out of 5 animals died on administration of 1 g./kg. and 5 out of 5 animals on administration of 1.5 g./kg., the mice being in a state of profound prostration until death).

The margin of safety is thus very considerably superior to that of reserpine whose DL_{50} when administered intraperitoneally in suspension is 7 mg./kg. under the same experimental conditions.

(b) *Chronic toxicity*.—6 groups of 10 young rats, each weighing, as an average, 10 g., received daily (except Sundays) for a month a subcutaneous injection of 10-chloro deserpine or, respectively, of reserpine in the following doses:

- 10 Group 1, controls: no treatment;
 Group 2: 10-chloro deserpine, 0.2 mg./kg.;
 Group 3: 10-chloro deserpine, 0.5 mg./kg.;
 Group 4: 10-chloro deserpine, 1 mg./kg.;
 Group 5: reserpine, 0.2 mg./kg.;
 Group 6: reserpine, 0.5 mg./kg.;

Reserpine caused a pronounced inhibition of growth in the doses employed and, with the dose of 0.5 mg./kg., even a loss of weight. Furthermore, 3 rats of group 5 and 2 rats of group 6 died.

The 3 groups treated with the various doses of 10-chloro deserpine showed, after a month of treatment, weight curves superimposable on those of the controls and their general state was satisfactory in all regards.

25 All these tests prove that 10-chloro deserpine is a far better tranquilizing agent than reserpine and that its toxicity and its potentiating effect on barbiturates are very surprisingly lower than those of reserpine. The new compositions, thus, represent a highly meritorious advance in the tranquilizer art.

30 It is, of course, understood that, in place of 10-chloro deserpine, its non-toxic, therapeutically active acid addition salts, such as the salts with hydrogen chloride, hydrogen bromide, nitric acid, sulfuric acid, phosphoric acid, perchloric acid, acetic acid, citric acid, oxalic acid, tartaric acid, ascorbic acid, methane sulfonic acid, hydroxy ethane sulfonic acid, p-toluene sulfonic acid, salicylic acid, p-amino salicylic acid, acetyl salicylic acid, nicotinic acid, and others can also be employed in the tranquilizing compositions, according to the present invention.

EXAMPLE 4

45 The active agent 10-chloro deserpine is obtained by proceeding, for instance, in the following manner:

50 5-chloro tryptamine is prepared as described by Abramovitch in "J. Chem. Soc." 1966, page 4599. It is purified by dissolving it in methylene chloride, passing carbon dioxide into the solution, and decomposing the separated addition product by heating.

55 Equimolecular amounts of the purified 5-chloro tryptamine and of the methyl ester of 1 β -carboxy methyl-2 β -methoxy carbonyl-3 α -methoxy-4 β -acetoxy-6 β -formyl cyclohexane are allowed to stand at room temperature for 15 minutes. Thereby, a solution of the methyl ester of 10-chloro-16 β -methoxy carbonyl-17 α -methoxy-18 β -acetoxy-(2-3),(3-4)-diseco-4^{1,21},20 α -yohimbene-3-carboxylic acid is obtained which is used without further purification in the following reaction step.

60 65 22 cc. of methanol are added to said methylene chloride solution obtained from 1 g. of 5-chloro tryptamine. After cooling the mixture to +5° C., 1 g. of potassium borohydride is added. The temperature of the mixture is maintained at +5° C. for 15 minutes and then at +20° C. for 30 minutes. Excess borohydride is destroyed by the addition of the minimum required amount of acetic acid. The solution is evaporated to dryness in a vacuum at a temperature not exceeding 20° C.

The residue is taken up with acetone. The solution is filtered and concentrated by distillation to a small volume. Ether is added and crystallization is initiated by scratching. After cooling in ice, the crystals are filtered off with suction. 10-chloro-18 β -acetoxy-16 β -methoxy carbonyl-17 α -methoxy-3-oxo-2,3-seco-20 α -yohimbane is obtained thereby.

administration of 1 mg./kg. of reserpine and that the effect of 50 mg./kg. of 10-chloro deserpine is much weaker than that with 5 mg./kg. of reserpine.

10-chloro deserpine, therefore, only exerts a depressive effect of about one-twentieth that of reserpine.

III. Eyelid drooping test

This test is based on the property possessed by compounds of the reserpine series of causing the eyelids to droop. The intensity of this effect is measured by the degree of narrowing of the palpebral slit, defined according to the scale as proposed by Ruben et al. "J. Pharmacol. Exp. Therap.", vol. 120, page 125 (1957).

Grade 0=no visible effect;

Grade 1=closing of the palpebral slit by one-fourth;

Grade 2=closing the palpebral slit by one-half;

Grade 3=closing of the palpebral slit by three-fourths;

Grade 4=complete closing the eyelids.

By adding the grade numbers determined on examining the eyes of a group of 5 rats according to the above given scale, whereby the total grade numbers may vary between 0 and 40, the degree of sedation can be expressed as of any given moment after injection.

Table III shows the grade numbers obtained on taking readings 5 hours or, respectively, 6 hours after intraperitoneal injection into rats of varying doses of 10-chloro deserpine and of reserpine. The effect of each dose reached its maximum at the moment of said readings and then stayed on a slightly fluctuating level. By combining said two values expressed in percentage of the highest possible effect, it is possible to calculate the ED_{50} (50% effective dose) according to the graphic method of Miller and Tainter. A comparison of the two ED_{50} proves that 10-chloro deserpine has only one-tenth of the effect of reserpine.

TABLE III.—COMPARISON OF THE EFFECT OF 10-CHLORO DESERPINE AND OF RESERPINE IN THE EYELID DROOPING TEST IN RATS

Compound injected	Dose in mg./kg.	5 hours after injection		6 hours after injection		Average effect per dose in percent of the maximum effect
		Test 1	Test 2	Test 1	Test 2	
10-chloro deserpine-----	1	9	11	9	9	23.7
	2	10	18	19	14	38.1
	5	25	29	25	30	68.1
Reserpine-----	0.1	1	2	0	1	2.5
	0.2	19	10	18	14	38.1
	0.5	26	28	31	26	69.4

ED_{50} of 10-chloro deserpine=2.40 mg./kg. $\pm$ 0.45 mg./kg.
 ED_{50} of reserpine=0.260 mg./kg. $\pm$ 0.019 mg./kg.

When using mice as test animals (see Table IV) the difference between the effects of the two compounds is even greater. 10-chloro deserpine has an eyelid drooping effect of only one-fortieth of that of reserpine.

TABLE IV.—COMPARISON OF THE ACTION OF 10-CHLORO DESERPINE AND OF RESERPINE IN CAUSING EYELID DROOPING IN MICE

Compound injected	Dose in mg./kg.	5 hours after injection		Average effect per dose
		Test 1	Test 2	
10-chloro deserpine-----	1	3	2	6.2
	2	0	0	0
	5	14	10	30
	10	27	29	70
	20	32	31	78.8
Reserpine-----	0.1	12	8	25
	0.2	24	27	63.7
	0.5	36	33	86.2
	1.0	38	35	91.4

ED_{50} of 10-chloro deserpine=7 mg./kg. $\pm$ 1.7 mg./kg.
 ED_{50} of reserpine=0.175 mg./kg. $\pm$ 0.029 mg./kg.

It may be especially pointed out that in mice the tranquilizing effect of 10-chloro deserpine has been established and has been found to be substantially equal to that of reserpine.

5

IV. Potentialization of the hypnotic effect of barbiturates

It is well known that compounds of the reserpine series cause prolongation of sleep induced by barbiturates. The following experiment was carried out in order to determine whether or not 10-chloro deserpine possesses this property.

Amytal was employed as barbiturate by reason of the brevity of its action when used alone.

10-chloro deserpine and reserpine were injected peritoneally into mice in groups of 10 mice. A dose of 80 mg./kg. of amytal was injected intravenously to one group of 10 mice serving as controls. The other group of mice received 1½ hours before administration of amytal either 10-chloro deserpine or reserpine. The duration of sleep was determined by the interval of time between the injection of amytal and the reappearance of the getting up reflex, whereby the mice returned to their upright position.

The results obtained thereby are shown in Table V, which indicates the duration of sleep in minutes for the two compounds according to the dose administered.

It is evident that while reserpine with doses of 0.5 mg./kg. and 2 mg./kg. significantly increases the duration of sleep induced by amytal, 10-chloro deserpine at the same doses, does not produce any significant increase in duration of sleep, when, of course, allowance is made for individual variations in animals receiving amytal only.

TABLE V.—ACTION OF 10-CHLORO DESERPINE AND OF RESERPINE ON THE DURATION OF SLEEP INDUCED BY AMYTAL IN MICE

Compound injected	Time of sleep in minutes
Amytal alone 80 mg./kg.	51 $\pm$ 9
10-chloro deserpine 0.5 mg./kg. plus amytal	68 $\pm$ 17
10-chloro deserpine 2 mg./kg. plus amytal	53 $\pm$ 7
Reserpine 0.5 mg./kg. plus amytal	101 $\pm$ 19
Reserpine 2 mg./kg. plus amytal	150 $\pm$ 20

V. Electric shock test on rats

It is well known that reserpine lowers the threshold of sensitivity to electric shock. This effect may be in relation to trembling and particular spastic symptoms in animals treated with high doses of reserpine. It may also be the cause of certain undesirable clinically observed effects during the course of treatment with this alkaloid.

75 The following experiment shows the results obtained in

This compound is saponified by means of N-sodium hydroxide solution by heating with stirring to 85° C. for one and one half hour, cooled, and rendered acid to a pH of 4.0 by the addition of acetic acid. The clear solution is extracted with methylene chloride in order to remove colored impurities. After decanting the organic layer, the aqueous layer is cooled in ice for one hour. The precipitated crystals of 10-chloro-16 β -carboxy-17 α -methoxy-18 β -hydroxy-3-oxo-2,3-seco-20 α -yohimbane are filtered with suction, washed with water, and dried at 40° C. Melting point 180-190° C.; rotatory power $[\alpha]_D^{20} = +31^\circ$ (concentration: 0.5% in ethanol).

Said carboxylic acid is pasted with methanol and a solution of diazomethane in methylene chloride, is added in small portions to said paste until the color of the reaction mixture remains yellow. The resulting solution is evaporated to dryness in a vacuum at 20° C. and the residue is taken up in acetone. Thereby, 10-chloro-16 β -methoxy carbonyl - 17 α -methoxy-18 β -hydroxy-3-oxo-2,3-seco-20 α -yohimbane is obtained.

This compound is dissolved in a mixture of pyridine and triethylamine (3:1). Nitrogen is passed through the solution and an excess of 3,4,5-trimethoxy benzoic acid anhydride is added thereto. The mixture is heated to 95° C. for 24 hours. After cooling, excess anhydride is destroyed by the addition of water. Methylene chloride and ice are added and the reaction mixture is acidified to a pH of 1.0 by the addition of hydrochloric acid. The organic layer is separated, washed with a sodium bicarbonate solution, dried, and evaporated to dryness. The residue is dissolved in a mixture of ethyl acetate and ether. On cooling in an ice bath for half an hour, 10-chloro-17 α -methoxy-16 β -methoxy carbonyl-18 β -(3',4',5'-trimethoxy benzoxyloxy)-3-oxo-2,3-seco-20 α -yohimbane is obtained.

Said ester is refluxed with about 5 times its amount of phosphorus oxychloride for one hour. The mixture is evaporated to dryness in a vacuum and the residue is taken up with methanol. 65% perchloric acid ($d=1.61$) and, thereafter, water are added to the solution while cooling. The yellow precipitate of the perchlorate of 10-chloro-17 α -methoxy-16 β -methoxy-carbonyl-18 β -(3',4',5'-trimethoxy benzoxyloxy)- $\Delta^{3(4)}$,20 α -yohimbane is filtered off with suction and washed with water.

The crude perchlorate is mixed with acetone, tetrahydrofuran, aqueous 13% perchloric acid solution, a small amount of ferric chloride, and zinc powder. The mixture is refluxed for 30 minutes and then filtered. The filtrate is concentrated by evaporation, mixed with water, and extracted with methylene chloride. The extracts are washed with dilute ammonia solution, dried over magnesium sul-

fate, and evaporated to dryness. The residue is dissolved in methanol. After the addition of 0.5 cc. of dilute nitric acid, the solution is cooled and crystallization is initiated by scratching. The yellow crystals of the nitrate of 10-chloro deserpidine are filtered off by suction and are suspended in methanol. On adding ammonia, 10-chloro deserpidine crystallizes. It is filtered, washed with methanol, and dried. The resulting 10-chloro deserpidine, i.e. 10-chloro - 17 α - methoxy - 18 β -(3',4',5'-trimethoxybenzoyloxy) - 16 β - methoxy carbonyl-3 β ,20 α -yohimbane crystallizes with $\frac{1}{2}$ mole of water and has a melting point of 160-170° C. and a rotatory power of $[\alpha]_D^{20} = -147^\circ$ (concentration: 0.5% in chloroform), and is insoluble in water and ether, slightly soluble in benzene, and soluble in acetone and chloroform.

We claim:

1. The process of tranquilizing persons and animals without exerting a substantial depressing effect upon the central nervous system, said process consisting in administering to persons and animals a compound selected from the group consisting of 10-chloro deserpidine and its therapeutically active acid addition salts in an amount between about 0.1 mg./kg. and about 0.5 mg./kg per day.
2. The process of tranquilizing persons and animals without exerting a substantial depressing effect upon the central nervous system, said process consisting in administering to persons and animals the levo-rotatory 10-chloro deserpidine in an amount between about 0.1 mg./kg. and about 0.5 mg./kg. per day.
